Primary Examiner — Justin C Dodson

Assistant Examiner — Matthew Bird

(74) Attorney, Agent, or Firm — Hemisphere Law, PLLC;
Zhigang Ma(57) **CLAIM**

The ornamental design for a watering device for plants as shown and described.

DESCRIPTION

FIG. 1 is a front and top perspective view of the watering device for plants, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the watering device for plants that form no part of the claimed design.
